Andrew D. Bochner**CLAIM**

The ornamental design for an interactive year calendar, as shown and described.

DESCRIPTION

FIG. 1 is a front view of the interactive year calendar showing our new design;

FIG. 2 is an enlarged portion taken from the circumscribed area shown in FIG. 1;

FIG. 3 is an enlarged portion taken from the circumscribed area shown in FIG. 1; and,

FIG. 4 is an enlarged portion taken from the circumscribed area shown in FIG. 2.

The broken line showing of portions of the claimed design is included for the purpose of illustrating environmental structure and forms no part of the claimed design.

The dash-dot line is included for the purpose of illustrating the circumscribed and enlarged area and forms no part of the claimed design.
